UNITED STATES PATENT OFFICE

2,495,205

SLIVER ROLL FORMING MACHINE

James Scott Brown, Arbroath, Scotland, assignor
to Douglas Fraser & Sons Limited, Arbroath,
Scotland, a corporation of Great Britain

Application September 19, 1946, Serial No. 697,942
In Great Britain December 22, 1944

Section 1, Public Law 690, August 8, 1946
Patent expires December 22, 1964

1 Claim. (Cl. 19—158)

1

This invention relates to sliver roll forming machines, and more particularly, though not exclusively, to machines for winding into rolls sliver of jute or other bast fibres.

In U. S. Patent No. 1,791,076, of which this application is an improvement, there is described a machine incorporating two half arbors unitary with large end discs carried by pivotal arms and adapted to be swung apart on completion of the roll winding operation to permit ejection of the finished roll. The machine also includes a roller or drum accommodated between the discs for driving the sliver roll by friction.

According to the invention I provide small diameter arbor-starting discs, that is, of a diameter which is only a fraction of the diameter of the finished sliver roll, and I secure to the arms guide cheek-plates which extend towards the back of the machine and which are formed with concave cutaways so as to extend partly around the discs, the concavities approximately fitting the rims of the discs. These cheek-plates are spaced apart a distance slightly exceeding the width of the roll and serve to keep the expanding roll in position and ensure the building up of the roll to the correct width.

On starting a sliver winding operation the discs are driven frictionally by rotary drivers for speeding up the half-arbor in starting the formation of a roll. As the discs are of small diameter, in contrast to that of the roll produced or to the discs of said patent, the space required between one machine and that next adjacent for manipulation of large rolls is greatly reduced.

With the use of the arbor-starting discs it is possible to reduce the diameter of the friction roll-driver drum.

The cheek plates cover the nip of the roll on the respective drum.

The cheek plates thus function as sliver conductors, the surfaces liable to contact with the ends of the roll having at most a limited frictional action on the roll.

The rearward extensions of the cheek plates are particularly useful in that together with a hanging vertical spring back flap of known construction, which serves to push the sliver forward towards the half arbors for a restart, the cheek plates form as it were a box container which serves to guide the sliver that continues to be fed during the few seconds in which the arms are descending for a restart.

The figure of the accompanying drawing is a part end elevation part vertical section of a sliver

roll forming machine according to the invention. The view shown in the drawing is taken approximately in a plane extending between the half arbors of the machine and shows the pertinent parts of the machine to which the present invention relates, when the arms, discs and cheek plates are in their elevated position at approximately the time when a roll or sliver is completed but has not been removed.

10 Referring to the drawing, there is provided on each half-arbor as 6 a small diameter arbor-starting disc 1, that is, of a diameter which is only a fraction of the diameter of the finished sliver roll 2, and I secure to the arms as 3 guide 15 cheek plates as 4 which extend from about the position of the arbor as shown towards the back of the machine and which are formed with concave cutaways so as to extend partly around the respective discs 1, the concavities approximately fitting the rims of the discs 1. These cheek-plates 4 are spaced apart a distance slightly exceeding the width of the sliver roll 2 and serve to keep the expanding sliver roll in position and ensure the building up of the sliver roll to the 25 correct width.

On starting a sliver winding operation the ends of the arms 3 carrying the half-arbor 6 are in their lower position so that the discs 1 are driven frictionally by rotary drivers as 5 for 30 speeding up the half arbors 6 in starting the formation of a sliver roll on the half arbors. As the discs 1 are of small diameter, the space required between one machine and that next adjacent for manipulation of large sliver rolls 35 is greatly reduced. The sliver winding operation is carried out in approximately the same manner as that disclosed in the U. S. patent referred to above, and the mechanism for swinging the arms 3 apart on completion of a roll-forming operation may be the same as disclosed in said patent, such features, however, form no part of the present invention.

40 The relative diameters of the half arbors 6, of the discs 1 and of the finished sliver roll will be 45 clear from the showing in the drawing.

With the use of the arbor-starting discs 1 it is possible to reduce the diameter of the friction driver drum 7 co-operative with the half arbors 6 and engageable with the sliver roll after 50 formation of the roll has started. The several drums 7 for a group of machines may be carried on a common shaft 9.

It is to be understood that the distance between the two parallel drivers 5 slightly exceeds the axial length of the drum 7, and that the

distance between the two cheek plates 4 slightly exceeds the axial length of the boss of the drum 7, so that when the arms 3 are lowered the discs 1 contact with the drivers 5, and the cheek plates 4 just clear the shaft 9 of the drum 7.

The cheek plates 4 cover the nip of the sliver roll on its driver drum 7.

The cheek plates 4 thus function as sliver conductors, the surfaces liable to contact with the ends of the sliver roll having at most a limited frictional action on the roll.

The rearward extensions of the cheek plates 4 are particularly useful in that together with a hanging vertical back flap 8 of known construction, which serves to push the sliver forwards towards the half-arbors 6 for a restart, the cheek plates 4 form as it were a box container which serves to guide the sliver that continues to be fed during the few seconds in which the arms 3 are descending for a restart.

What is claimed is:

In a sliver roll-forming machine incorporating a pair of rotatable half-arbors, arbor-starting roll-confining discs, one on each half-arbor and rotatable therewith, a pair of spaced pivoted arms each carrying a half-arbor and disc, rotary drivers engageable with said discs at the start of a roll-forming operation, a driver-drum sepa-

rate from said rotary drivers and non-coaxial therewith arranged to engage with the sliver roll on said half-arbors after formation of said roll has started, said arbor-starting roll-confining discs being of substantially smaller diameter than that of the sliver roll when fully formed, and a cheek plate secured to each arm partially embracing the periphery of the disc carried thereby and extending toward the back of the machine, the cheek plates being of sufficient width to cover the nip of the sliver roll with the driver-drum until the sliver roll is fully formed, and said discs being of a diameter substantially less than the distance between the upper and the lower boundary edges of the cheek plates.

JAMES SCOTT BROWN.
